UNITED STATES PATENT OFFICE.

WALTER R. SCHLAGE, OF SAN FRANCISCO, CALIFORNIA, ASSIGNOR TO SCHLAGE LOCK COMPANY, OF SAN FRANCISCO, CALIFORNIA, A CORPORATION OF CALIFORNIA.

ESCUTCHEON-PLATE FASTENER.

Application filed August 2, 1923. Serial No. 655,221.

This invention relates to an escutcheon plate for door locks and the like and especially to means for securing the escutcheon plate against removal with relation to the door and the lock housing.

The object of the present invention is to generally improve and simplify the construction and operation of securing mechanisms of the character described; to provide a mechanism which permits an escutcheon plate to be readily and quickly attached to a door lock and rigidly secured when applied; a mechanism which also permits easy removal of the escutcheon plate for inspection, repair of the door lock, etc.; a mechanism which eliminates the use of exterior screws and like fastening means; and furthermore a mechanism of this character which is spring actuated and as such prevents loosening or rattling of the escutcheon plate and accidental release of the same.

One form which my invention may assume is exemplified in the following description and illustrated in the accompanying drawings, in which—

Fig. 1 is an edge view of a door partially in section showing the application of the invention.

Fig. 2 is a perspective view of one of the plates employed in connection with the door lock housing and the spring, said view also showing the spring actuated latch whereby the escutcheon plate is secured.

Fig. 3 is a front view of the escutcheon plate.

Referring to the drawings in detail, and particularly to Figs. 1 and 2, A indicates an ordinary door, 2 the latch plate, 3 the latch by which the door is locked or unlocked, 4 the lock housing, 5 and 6, the exterior escutcheon plates enclosing the lock housing, 7 the door lock spindle, and 8 the knobs whereby the spindle is turned. The lock housing employed in this instance also embodies a clamping plate such as indicated at 9. This plate engages one face of the door and it serves the function of securing the lock housing 4; that is, a pair of screws is carried by the plate 9 and these screws have a threaded engagement with the housing 4, thus securing the same against removal. The plate 9 is merely a clamping plate and as it cooperates with the housing 4, it may be said that it forms a part of the lock housing. An escutcheon plate is therefore pro-

vided to serve as a cover for the same, and the present invention is restricted to means for securing the escutcheon plate 6 with relation to the lock housing or, in other words, the plate 9.

The plate 9, as shown in Fig. 2, is disk like and circular in formation. It is provided with a central bearing 11 through which the spindle 7 extends, and it is also provided with perforations through which the screws 10 are passed. Formed in the lower edge of the plate 9 is a recess 12 and secured to the exterior face of the plate as indicated at 13 is a spring latch 14. This latch exerts an upward pressure in the direction of arrow a (see Fig. 1) and it cooperates with the recess 12 to secure the escutcheon plate 6. The escutcheon plate may have any shape desired but it is more or less essential that it be provided with an annular inturned flange such as shown at 15 which is adapted to embrace the outer edge or periphery of the plate 9. The lower portion of the annular flange 15 is bent inwardly as indicated at 16 and as such forms a hook like member which is adapted to engage the recess 12. The center portion of the escutcheon plate is cut away as at 17 to permit the escutcheon plate to be slipped over the spindle 7, and it is furthermore provided with a rectangular shaped recess 18 to permit the spring latch 14 to pass therethrough.

In actual operation with the lock housing 4 and the clamping plate 9 in place, it is only necessary to insert the screws 10 to secure the lock rigidly in place. After this has been accomplished the escutcheon plate is slipped over the end of the spindle and it is there fastened by engaging the hook or inturned flange portion 14 with the recess 12, and then pressing it inwardly over the latch 14. The latch thus passes through the recess 18 and an interlock is formed which secures the escutcheon plate to the clamping plate. The knob 8 may then be applied and the entire operation of installing the lock is completed.

An escutcheon plate which is secured in the manner here described is constantly held in position by the tension of the spring latch, and also by the interengagement of the hook 16 with the recess 12. As this is the case it can readily be seen that rattling and loosening of the plate cannot take place as it is

constantly held in place by the upward tension of the spring latch. The plate is quickly and readily applied when the lock is installed, and it may just as readily be removed if it is necessary to inspect or repair the lock as it is only necessary to depress the latch 14 by the finger and to wedge the plate off the annular flange of the plate 9 by means of a screw driver or the like. The fastening means here employed is of further importance as it eliminates the use of exterior screws. The ornamental appearance of the plates is thus improved, and the entire structure is given a plain and substantial appearance.

While the fastening means here shown is more or less specifically illustrated, I wish it understood that various changes in form and proportion may be resorted to within the scope of the appended claims; similarly, that the materials and finish of the several parts employed may be such as the experience and judgment of the manufacture may dictate or various uses may demand.

Having thus described my invention, what I claim and desire to securely by Letters Patent is—

1. The combination with the housing of a door lock and an escutcheon plate therefor, of a hook like member on the escutcheon plate engageable with the door lock housing, and a spring actuated latching member co-operating therewith to secure the escutcheon plate on the housing.

2. The combination with the housing of a door lock, of an escutcheon plate forming a cover therefor, said plate having a flange formed thereon which surrounds and embraces the lock housing, a projecting lug on the housing, an interengaging member formed on the escutcheon plate, and a spring latch carried by the housing and engageable with the escutcheon plate to secure the same against removal.

3. In a lock of the character described, a circular plate forming a portion of the lock housing, a circular shaped escutcheon plate forming a cover therefor, said plate having an annular flange formed thereon embracing the lock housing plate, a lug on the flange of the escutcheon plate adapted to interlock with the lock housing plate, a notch formed in the escutcheon plate near the center portion thereof, and a spring latch carried by the lock housing plate and adapted to project through said notch to engage and secure the escutcheon plate.

4. In a lock of the character described a lock housing, a central hub portion thereon, an escutcheon plate forming a cover for the lock housing, said plate having a central opening formed therein in alignment with the hub on the lock housing, and a spring latch carried by the hub and adapted to engage the peripheral edge of the central opening in the plate to secure the same to the lock housing.

WALTER R. SCHLAGE.
